UNITED STATES PATENT OFFICE

121,769

DESIGN FOR A PORTABLE GRINDER

Francis A. Jimerson, Athens, Pa., assignor to
Ingersoll-Rand Company, New York, N. Y., a
corporation of New Jersey

Application November 17, 1939, Serial No. 88,338

Term of patent 14 years

To all whom it may concern:

Be it known that I, Francis A. Jimerson, a citizen of the United States, residing at #743 South Main Street, Athens, in the county of Bradford and State of Pennsylvania, have invented a new, original, and ornamental Design for Portable Grinders, of which the following is a specification, reference being had to the accompanying drawing, forming part thereof.

In the drawing Fig. 1 is a side elevational view of a portable grinder showing my new design.

Fig. 2 is a top plan view of the same.

Fig. 3 is an elevational view of the grinder opposite that shown in Fig. 1.

I claim:

The ornamental design for a portable grinder, as shown.

FRANCIS A. JIMERSON.
